UNITED STATES PATENT OFFICE.

NELSON K. SMITH, OF DALLAS, TEXAS.

WRENCH.

1,397,884.

Specification of Letters Patent. Patented Nov. 22, 1921.

Application filed December 27, 1920. Serial No. 433,207.

To all whom it may concern:

Be it known that I, NELSON K. SMITH, a citizen of the United States, residing at Dallas, in the county of Dallas and State of Texas, have invented certain new and useful Improvements in Wrenches, of which the following is a specification.

This invention relates to new and useful improvements in wrenches.

The object of the invention is to provide a wrench of the sliding jaw type in which the movable jaw is arranged to rock to take a better "bite" on the object engaged. The particular object of the invention is to provide means for effecting an intermediate adjustment of the sliding jaw after the same has been adjusted by sliding it into the tooth or notch nearest the size desired; thereby affording a much closer adjustment than can be obtained by the sliding adjustment of the jaw and producing a more efficient and satisfactory tool.

A construction designed to carry out the invention will be hereinafter described together with other features of the invention.

The invention will be more readily understood from a reading of the following specification and by reference to the accompanying drawings, in which an example of the invention is shown, and wherein:

Figure 1 is a side elevation of a wrench constructed in accordance with my invention,

Fig. 2 is a front elevation of the same,

Fig. 3 is a detail showing the sliding jaw in section,

Fig. 4 is a cross section on the line 4—4 of Fig. 3,

Fig. 5 is a cross section on the line 5—5 of Fig. 3,

Fig. 6 is a perspective view of the rocking pin,

Fig. 7 is a side elevation of a modified form of wrench,

Fig. 8 is a front elevation of the same,

Fig. 9 is a sectional view,

Fig. 10 is a cross section on the line 10—10 of Fig. 9,

Fig. 11 is a perspective view of the intermediate adjusting device for the wrench shown in Figs. 7 to 10 inclusive,

Fig. 12 is a side elevation of another form of the wrench,

Fig. 13 is a front elevation of the same,

Fig. 14 is a sectional detail of the same,

Fig. 15, is a cross section on the line 15—15 of Fig. 14,

Fig. 16 is a side view of a swinging sliding jaw type of wrench equipped with my invention,

Fig. 17 is a rear elevation of the same,

Fig. 18 is a cross section on the line 18—18 of Fig. 17, and

Fig. 19 is a sectional detail of a square jaw wrench embodying the invention.

In the drawings the numeral 10 designates a shank which may assume the various shapes shown in the different figures; the lower portion of the shank constituting a handle. The shank has vertical channels 70 11 on each side extending upwardly from its bottom about two-thirds of its length, which is optional; thus forming lateral ribs 12 on each side of the front edge and lateral ribs 13 on each side of the rear edge. 75 This reduces the weight of the shank but gives reinforced front and rear edges which are desirable. In various figures of the drawings, except Fig. 19, I have shown the shank having a fixed jaw 14 at its upper end 80 provided with teeth, which may be disposed on an incline if desired. In Fig. 19 I have shown a square fixed jaw, which is especially adapted for use on nuts and glands. It is pointed out that the jaws of the wrench may 85 have different forms according to the purpose for which the wrench is designed.

In Figs. 1 to 6 inclusive I have shown a sliding jaw which includes a yoke 15 embracing the shank 10. The yoke is provided 90 with teeth 16 which may be disposed on an incline. The jaw has a depending central arm 17 which is reduced in thickness and enters between the ears 18 of a collar 19 which surrounds the shank. The collar 19 95 has a fulcrum boss 20 on its inner side disposed to engage notches 21 in spaced relation on the rear edge of the shank. The collar is angular as is best shown in Fig. 5, and has its rear side 22 provided with serrations or otherwise roughened and is given a slight upward and inward inclination; whereby the operator may more efficiently engage his thumb and slide the jaw on the shank. The downward movement of the 100 jaw is limited by a shoulder 23 on the rear of the shank. The toothed or serrated end 16 is regarded as the forward end of the jaw, and the opposite end adjacent to the pivot 24 as the rear end of the jaw.

A rocking pin 24 is mounted transversely in the ears 18 and the arm 17 is notched at 17' to receive the pin; whereby it is pivoted so as to rock or swing on said pin. The 5 notch 17' is greater than a semi-circle and the arm is thus confined on said pin. Within the yoke the sliding jaw has a horizontal recess 25 in which a coiled spring 26 is confined and bears against the inner end of a 10 plunger 27 which is forced outwardly into engagement with the front edge of the shank, whereby the rear of the yoke is held in contact with the rear edge of the shank as is best shown in Fig. 3. In the lower end 15 of the arm a vertical recess 28 receives a coiled spring 29 which bears against a plunger 30. The plunger 30 is forced downwardly so as to bear on a transverse web 31 connecting the lower ends of the ears 18. 20 The plunger 30 is located between the notch 17' and the front edge of the arm. The outer ends of both plungers are rounded so as to ride on the surfaces which they engage. It will be seen that the arm and yoke are 25 pivoted so as to rock on the pin and swing relatively of collar 19 and also that the collar 19 is arranged to swing so as to cause the fulcrum boss 20 to ride out of one notch 21 and into the next one. The function of 30 the plunger 27 is to swing the yoke away from the shank 10 and thus draw the rear side of said yoke into contact with the rear edge of the shank and also to hold the boss 20 in the notches 21. 35 The pin 24 has an angular recess 32 having substantially the same width as the front edge of the shank as is best shown in Fig. 5. An adjusting wedge or key 33 has a head 34 at its lower end provided with a finger 40 grip 35 and rearwardly extending fingers 36, which fingers are shouldered so as to embrace the ribs 12 and engage in the channels 11. The wedge has a vertical central tongue 37 engaging in the vertical groove 38 in the front edge of the shank, whereby 45 the wedge may be slid vertically and is held against lateral displacement. At its upper end the wedge has a stud 39 projecting outwardly into a vertical groove 40 in the inner 50 face or edge of the arm 17, whereby the upward and downward movement and particularly the latter, is limited. That side of the wedge engaging with the edge of the shank is perpendicular while the front side is inclined, and engages in the recess 32 of the 55 pin 24.

By inclining the teeth of the jaws it is obvious that when a round article such as a pipe is engaged, said teeth will more readily bite into the pipe, when the shank of the wrench is given a slight rotative movement. This may be accentuated by disposing the teeth 16 at a slightly different inclination from that of the teeth of the jaw 14. In 60 using the wrench the jaw 14 is engaged over

or around the article to be gripped, and the sliding jaw is slid toward said article until the teeth 16 engage the same. The adjustment of the sliding jaw ordinarily is controlled by the relation of the notches 21 and 70 it frequently happens that the teeth 16 cannot be brought into close enough engagement with the article because the last notch into which the boss 20 may be moved causes the jaw to be positioned too far from the 75 article which it is desired to grip. It is in such instances that my improvement is of the greatest value. When this occurs it is merely necessary to push the wedge 33 toward the jaws. It will be seen that the pin 80 24 is located below the boss 20 and consequently when the wedge is moved upwardly said pin will be displaced outwardly or away from the shank, whereby the sliding jaw will be fulcrumed on the boss 20 and 85 the arm and yoke swung upwardly so that the teeth 16 will bite into the article which it is desired to grip. During this movement the arm 17 may undergo an individual swinging movement and the plunger 30 acts 90 to keep the parts in proper relation and maintain the bite on the article. It will be seen that a considerable intermediate adjustment may be had by means of the wedge 33. It is also pointed out that as the collar and 95 ears are swung upward the inner edge of the arm 17 is swung toward the shank so that the groove 40 assumes a more nearly perpendicular position. Owing to the flat surface of the recess 32 and the inclination 100 of the web, the parts will remain at the intermediate adjustment which is made. The wrench may be instantly released by engaging the finger grip 35 and pulling the wedge downwardly. The jaw may be slid downwardly by engaging the serrations 22 with the thumb and merely pulling the jaw away from the jaw 14.

It will be seen that the arm 17 is at all times free to rock on the pin 24 and a better 110 grip may thus be had on the article. It is also pointed out that before the wedge 33 is brought into use the arm will usually be displaced toward the shank and thus the adjustment of the wedge will have an immediate effect which will result in an instantaneous action. It is also pointed out that the plunger 30 tends to hold the ears in position when the arm 17 is swung toward the shank and prevents play. The form of 115 wrench which has been described is extremely convenient and may be easily manipulated with one hand. The jaw may be slid up and down by merely pushing on the same and the wedge 33 is operated as easily. 120

It is obvious that the invention may be carried out in numerous ways and various constructions may be evolved for effecting the intermediate adjustment. In Figs. 7 to 11 inclusive I have shown one of these 130

modified forms in which the wedge is omitted and an eccentric 41 is placed in the notch 17'. The eccentric has trunnions 42 pivoted in the ears 18. The lower end of 5 the arm 17 is reduced at 17^a so as to be received in a bracket 43 which extends radially from the eccentric with relation to its trunnions and carries a thumb plate 44 which latter swings over the front edges of 10 the ears 18. The web 31 is slotted at 45 to receive the bracket 43 when the latter is swung downward, the web projecting through the bracket and supporting the plunger 30. The front edge of the shank 15 10 is smooth. The displacement of the sliding jaws for the intermediate adjustment is exactly the same as where the wedge is used. By placing the thumb on the plate 44 and swinging the bracket 43 20 upwardly, the eccentric 41 is rocked over against the front edge of the shank 10 whereby the jaw is swung on the boss 20 and displaced upwardly as well as arcuately. The parts are released by swinging the 25 bracket 43 downward to its normal position.

In Figs. 12 to 15 inclusive I have shown another form which is somewhat similar to the first form described and which 30 employs a wedge 33' substantially the same as the wedge 33. This wedge has a tongue 37' engaging in a groove 38' in the shank, and is also provided at its upper end with a stud 39' engaging in a groove 40' in the 35 arm 17. In this form the collar 19 has depending ears 18' of a slightly different shape from the ears 18 and connected at their lower ends by an arcuate web 31'. In place of the pin 24, a rounded boss 46 is provided at the lower end of the arm and a pin 47 in concentric relation to said boss passes therethrough and engages in the ears 18'. The boss rests in the arcuate web 31' as is 40 shown in Fig. 14. The wedge 33' engages 45 the inner portion of the web instead of engaging the pin and is given a curved face instead of a straight face. The action however is just the same, because when the wedge is pushed upward the sliding jaw is 50 swung arcuately and upwardly, being displaced from the shank by means of the web. The other parts of the wrench are exactly 55 the same as in the other form. This form while operative is not as desirable as the other forms which have been described.

The invention may be embodied in the well known overhanging sliding jaw type of wrench and such is shown in Figs. 16, 17 and 18. The shank 10 has a fixed jaw 14' at its upper end provided with the usual teeth. A sliding jaw 51 overhangs the jaw 14' and is provided with co-acting teeth in the usual manner. The jaw 51 has a depending body 52 extending through the 60 yoke 48 and terminating in a tongue 53 at 65 its lower end. The tongue fits in the upper slotted end of an arm 54 and these parts are pivoted together by a transverse pin 55. A spring pressed plunger 56 is mounted in the jaw 14' and projects from the rear 70 side thereof so as to bear against the body 52 and tends to force said body away from the jaw and to swing the yoke 48 downwardly. A collar 57 embraces the shank 16 and also 75 receives the arm 54. This collar has a fulcrum boss 20' engaging the notches 21' and carries a transverse rocking pin 24' having an angular recess 32'. The pin is confined in a notch 58 in the arm. A wedge 59 80 engages in a groove 60 in the rear space of the shank and the arm 54 is recessed to receive said wedge. A spring pressed plunger 61 mounted in the lower portion of the arm engages notches 62 in the adjacent 85 face of the wedge. The wedge has an out turned finger grip 63 at its lower end. The operation of the wedge is opposite from that described in connection with the other forms of wrenches. The jaw 51 is adjusted with 90 relation to the jaw 14' by sliding the collar 57 up and down the shank 10, the yoke 48 remaining relatively stationary. By reason of the swinging yoke 48 and the pivoted joint between the body 52 and arm 54, the 95 jaw may be slightly rocked to afford a better bite on the article to be gripped as is usual in this style of wrenches. For effecting the intermediate adjustment, the user grasps the part 63 and pulls the wedge 59 100 downwardly so that its inclined face slides through the recess 32' of the pin. The pin being above the fulcrum boss, it is obvious that the collar will be swung downwardly as well as arcuately thus pulling the jaw 105 51 down onto the article to be grasped. It is necessary to employ the plunger 61 to hold the wedge in its adjusted position. The parts may be readily released by pushing the wedge upwardly as is obvious. The 110 same principle is involved and the relation of the parts is merely reversed.

In Fig. 19 I have shown what is called a square or straight jaw 64 at the upper end of the shank 10 and a corresponding sliding 115 jaw 65 on the shank. This type is often referred to as a "monkey" wrench. The jaw 65 has a yoke 66 embracing the shank 10. A collar 67 has a fulcrum boss 68 engaging notches 69 on the rear edge of the shank. 120 An arm 70 has a rounded boss 71 at its lower end engaging in an arcuate notch 72 formed in a web 73 at the front of the collar. A coiled spring 74 is confined in the upper end of the web and is seated in the 125 arm above the boss 71. The arm at the rear of the boss has an inclined face 75 disposed to be engaged by a wedge 76 which has a tongue 77 sliding in a groove 78 in the front end of the shank. The wedge has a stud 79 130

at its upper end sliding in a vertical groove 80 in the jaw 65. After the jaw 65 has been adjusted as close as possible to the work by sliding it on the shank, a further or intermediate adjustment is often necessary. The arm 70 is arranged to rock on the collar 73 and the sliding jaw is displaced upwardly and arcuately by sliding the wedge 76 upwardly, whereby an intermediate adjustment 10 is had as in the other forms.

Various changes may be made in the dimensions and locations of the parts and various modifications and structural changes may be made within the scope of the invention and without departing from the spirit 15 thereof.

What I claim, is:

1. In a wrench, a shank having a fixed jaw secured thereto, a sliding jaw fulcrumed 20 on the shank, and adapted to be moved longitudinally of said shank, and means for swinging the jaw on its fulcrum toward the fixed jaw to effect an intermediate adjustment thereof and positively holding the sliding jaw in the adjusted position.

2. In a wrench, a shank having notches in one of its edges, a fixed jaw on the shank, a sliding jaw having a fulcrum member to engage the notches of the shank and adapted 30 to swing upon the fulcrum member toward the fixed jaw, and means for displacing one end of the sliding jaw from the shank, whereby said jaw is swung on its fulcrum member toward the fixed jaw.

3. In a wrench, a shank having a fixed jaw at one end, a sliding jaw adjustable longitudinally of the shank, said sliding jaw being fulcrumed intermediate its forward and rear ends on one edge of the shank, and 40 means engaging the sliding jaw at a point off-set longitudinally of the shank from the fulcrum point of said jaw for displacing the jaw from the shank and swinging it on its fulcrum toward the fixed jaw and positively holding the sliding jaw in the adjusted position.

4. In a wrench, a shank having a fixed jaw at one end, a collar surrounding the shank and adjustable longitudinally thereof, a fulcrum boss within the collar engaging one edge of the shank, a jaw member pivoted in the collar, and means engaging between the edge of the shank opposite from

the fulcrum and the pivoted jaw member for swinging the collar on its fulcrum and displacing the pivoted jaw member toward the fixed jaw. 55

5. In a wrench, a shank having a fixed jaw at one end, a collar surrounding the shank and adjustable longitudinally thereof, a fulcrum boss within the collar engaging one edge of the shank, a jaw member pivoted in the collar, means engaging between the edge of the shank opposite from the fulcrum and the pivoted jaw member for swinging the collar on its fulcrum and displacing the pivoted jaw member toward the fixed jaw, and a yoke connecting the pivoted jaw member and the shank. 60 65

6. In a wrench, a shank having a fixed jaw at one end, a collar surrounding the shank and adjustable longitudinally thereof, a fulcrum boss within the collar engaging one edge of the shank, a jaw member pivoted in the collar, and an adjustable element movable within the collar and engaging the edge of the shank opposite from that engaged by the fulcrum boss for swinging the collar on its fulcrum boss and moving the pivoted jaw member into closer relation 80 to the article gripped between the jaws. 75

7. In a wrench, a shank having a fixed jaw at one end, a collar surrounding the shank and adjustable longitudinally thereof, a fulcrum boss within the collar engaging one edge of the shank, a jaw member pivoted in the collar, and a wedge slid able on the shank for swinging the collar on its fulcrum. 85

8. In a wrench, a shank provided with a longitudinal set of notches, a jaw carried by the shank, a member adapted to be moved longitudinally of the shank and provided with a fulcrum element to engage within a selected notch, said fulcrum element serving 95 to normally hold the member against longitudinal movement with relation to the shank and also serving as a pivot joint upon which the member may be turned when said member is swung toward the said jaw, means to 100 swing the member upon the fulcrum element toward the said jaw and to positively hold the same in the adjusted position, and a co-acting jaw carried by said member.

In testimony whereof I affix my signature. 105
NELSON K. SMITH.
